UNITED STATES PATENT OFFICE.

NICOLA STRAMAGLIA, OF CHICAGO, ILLINOIS.

CENTRIFUGAL DRIER.

Application filed June 11, 1927. Serial No. 198,028.

My invention relates to improvements in laundry devices and more particularly to that type of laundry apparatus designed for the semi-drying of washed fabrics and garments 5 preliminary to ironing and airing.

The object of my invention is to provide a centrifugal drier of the kind described which will permit of a more convenient and expeditious handling of laundry goods.

10 A more particular object of my invention is to provide an improved apparatus of simple construction by means of which garments and fabrics after washing may be placed in a hopper, given a preliminary drying and then 15 quickly dumped by the novel means forming a part of the present invention.

Another object of my invention is to provide novel means for handling garments and fabrics in a manner to obviate damaging or 20 tearing same.

Other objects and advantages of the methods and means employed will appear more fully hereinafter as set forth in the detailed description, reference being had to the 25 accompanying drawing in which:—

Figure 1 is a side elevation of my device partly in cross section showing the apparatus as it appears in actual operation.

Figure 2 is a vertical cross section of an 30 embodiment of my invention.

Figure 3 is a cross section taken on line 3—3 of Figure 2.

Figure 4 is a plan view of the turn table as 35 shown with the hopper removed and with a part broken away to show the roller bearing.

Figure 5 is a detailed view of a driving clutch member.

Referring more particularly to the drawings in which similar characters of references 40 apply to like parts in the several views, 10 is an outlet valve of a container 11, having a lid 11', an inclosing wall 12 and a bottom 13. 14 is a hopper received by container 11,—the hopper having draining perforations 15, and 45 compartments 17 and 18, formed by web 19, having a socket 20, adapted to receive the squared shoulder 21, of a divided shaft 22 having an upper section 22' provided with a female clutch part 23, and a lower section 24 50 having a male clutch member 25', forming the complete clutch 25. Keyed to an intermediate part 26, of the upper section 22' of the shaft 22, is a turn table 50 having the flange 50', rotatably supported on the container 55 bottom 13, by roller bearings 27.

The hopper 14, is closed at its lower end by folding, collapsible bottoms 51 and 52 connected to web 19 by hinges 28 and 29,—bottoms 51 and 52 being adapted to be held in normal position as shown in Figure 2, by 60 spring-impelled latches 30, registering in sockets 31 in the walls of the hopper 14. The hopper 14, while removably mounted, seats firmly on the shaft 22. The latches are released when desired, by the latch strings 32 65 which are united in the draw cord 33 after passing over the trunnions 34. The shaft 22 is also provided with a stuffing box 35 and a thrust bearing 36, supported by bracket 37, bolted to rigid floor extension 38. A collar 39 on the upper section 22' of the shaft 22, impinging against bracket 37, serves to prevent vertical shifting of the shaft 22.

On an overhead track 40, a member 41, provided with guide wheels 42, running on track 75 40, and provided also with supporting trunnions 43 serves as a crane to lift and convey the hopper 14. A belt 44, is additionally provided to be connected to the male clutch member as a further source of optional power, 80 when desired.

The mode of operation of my device will now be obvious upon referring to the drawing and is briefly as follows:—

Garments and fabrics, after the preliminary wet wash, are placed in the hopper 14 which is either directly in the container 11 or optionally conveyed to the container by the overhead traveling crane. Upon revolution of the shaft 22 through the intermediary of 90 the expansion centrifugal clutch which binds both members of the clutch into frictional engagement under normal speeds of the power shaft 22—the hopper is revolved and the water in the garments and fabrics, following the well known centrifugal process, flies tangentially from the periphery of the hopper through the perforations 15 and thence to the floor bottom of the container, where it is drained by means of the outlet valve 10. The 95 double compartment in the hopper provides a ready means of dividing the fabrics and garments into two different groups, if desired, for their better subsequent classification.

By the method and means shown, I have 105 been able to effect a substantial saving of time and labor in handling the wet wash of a laundry. In the provisions of the novel hinged bottoms and latches for the dumping of the wash, I have also been able to prevent catch- 110

ing of the fabrics on projecting points, thereby, avoiding much consequent damage to garments of more delicate texture. It is obvious that a pull on the draw cord 33 will suffice to 5 disengage the resilient latches from the wall of the container, whereupon the hinged bottoms fold downwardly into the position shown in Figure 1 permitting the wash to be conveniently placed on a table or wherever 10 desired. If desired, either of the compartments 17 and 18 may be individually dumped by pulling its respective latch string 32 in the manner indicated. It is, of course, understood that the drying of garments and fabrics in the hopper is carried only to a point 15 best suited for subsequent ironing.

While I have shown and described a preferred embodiment of the various parts, it will be understood that the device is susceptible of modification without departing from 20 the essential feature of, or sacrificing any of the advantages thereof, and, hence, I do not wish to be understood as limiting myself to the precise arrangement and formation of the 25 several parts herein shown but desire to avail myself of such variations and modifications as fairly fall within the scope of the appended claims.

What I claim as new, and desire to secure 30 by Letters Patent is:

1. A centrifugal drier comprising a container, a revolving hopper secured to a web having a socket adapted to receive a shaft, said web being secured to the inner periphery 35 of said hopper, a plurality of bottoms hingedly secured to said web, and means to releasably lock said bottoms to said container whereby the bottoms may be selectively, separately and simultaneously supported and 40 collapsed as desired.

2. A centrifugal drier comprising a container, a hopper removably and operatively mounted on revolvable shaft, a central compartment dividing web in said hopper, a pair 45 of folding bottoms hinged to the web, and

means to support and collapse said bottoms when desired.

3. A centrifugal drier comprising a container, a hopper having compartments and a circumferential wall, said hopper being removably and operatively mounted on a revolvable shaft, a collapsible bottom hingedly connected to a central web secured to said circumferential wall, said hopper releasably supported against the circumferential wall, 55 and means whereby the hopper with material contained therein, may be raised, manipulated and dumped while in a vertical position.

4. A centrifugal drier comprising a container, a power actuated shaft in said container, a removable hopper provided with a web having a socket adapted to register with said shaft, a bottom centrally divided and hinged to the web, and means on the bottoms to releasably support and collapse said bottoms, when desired.

5. A centrifugal drier, comprising an outer container, a hopper in said container having a central compartment dividing web, and a collapsible bottom consisting of two flaps hingedly connected to the central web, means in said web providing a socket adapted to removably seat on a power actuated shaft, means integral with the hopper to drain liquid from said hopper while revolving, and 75 means to releasably support and dump when desired said collapsible bottom.

6. A centrifugal drier, comprising an outer container, an inner revolvable hopper including a circumferentially perforated inclosing wall, a center web secured to and dividing said hopper into two compartments, means in said web to receive and be actuated by a power operated shaft, and releasable means to support and dump material selectively in either 80 compartments and simultaneously in both compartments, substantially as described.

In testimony whereof I have signed my name to this specification.

NICOLA STRAMAGLIA.
